(57) **CLAIM**

The ornamental design for a zafu, as shown and described.

DESCRIPTION

FIG. 1 is rear perspective view of a zafu (meditation cushion) showing the new design, shown with its ankle pad in a stowed position;

FIG. 2 is a rear view thereof;

FIG. 3 is front view thereof;

FIG. 4 is side view thereof;

FIG. 5 is an opposite side view thereof;

FIG. 6 is a top view thereof;

FIG. 7 is a bottom view thereof;

FIG. 8 is a rear perspective view thereof, shown with its ankle pad in a deployed position.

FIG. 9 is a rear view thereof;

FIG. 10 is a front view thereof;

FIG. 11 is a side view thereof;

FIG. 12 is an opposite side view thereof;

FIG. 13 is top view thereof; and,

FIG. 14 is a bottom view thereof.

The broken lines shown in the drawings represent portions of the zafu that form no part of the claimed design. The shading shown in the drawings does not represent surface decoration.

1 Claim, 8 Drawing Sheets
